CLAIM

The ornamental design for a beverage cooler, as shown and described.

DESCRIPTION

FIG. 1 is a top-front-right perspective view of a beverage cooler showing my new design;

FIG. 2 is a bottom-rear-right perspective view thereof;

FIG. 3 is a front elevational view thereof;

FIG. 4 is a front elevational view thereof, showing the strap folded;

FIG. 5 is a rear elevational view thereof;

FIG. 6 is a left-side elevational view thereof;

FIG. 7 is a right-side elevational view thereof;

FIG. 8 is a top plan view thereof;

FIG. 9 is a bottom plan view thereof; and,

FIG. 10 is a top-front perspective view of a beverage cooler in a state of use thereof, showing the top lip folded down. The stitching shown in broken lines in FIGS. 1-7, and 10 forms a part of the claimed design. The cup shown in dashed lines in FIG. 10 illustrates environment and forms no part of the claimed design.

The stippling shown in FIGS. 1, 3, 4, 6, 7, and 10 depicts a contrast in appearance.
